Patented Apr. 12, 1921.

Inventor:
Irena T. Syverson,
by: John E. Shyres
Attorney.

UNITED STATES PATENT OFFICE.

LENA J. SYVERSON, OF IRONTON, MINNESOTA.

LAUNDRY-STRAINER.

1,374,338.

Specification of Letters Patent. Patented Apr. 12, 1921.

Application filed June 19, 1919. Serial No. 305,303.

To all whom it may concern:

Be it known that I, LENA J. SYVERSON, a citizen of the United States, residing at Ironton, in the county of Crow Wing and State of Minnesota, have invented new and useful Improvements in Laundry-Strainers, of which the following is a specification.

My invention relates to improvements in laundry strainers.

10 Its object is to facilitate the removal of washed articles from a laundry boiler and to conveniently and quickly compress excess moisture from such articles.

15 A further object is to remove boiled articles from hot water without wetting or burning the hands of the laundress.

Figure I is an elevation of my device in operative position in a laundry boiler, with the squeezer elevated. Fig. II is a similar view 20 with the squeezer depressed and Fig. III is a perspective view of my device.

25 My device comprises a foraminous receptacle or tray A and a foraminous squeezer B, the latter being articulated at one end to the receptacle by the hinge 10. The receptacle A consists of a frame 11, preferably of metal rods, to which is attached the wire mesh fabric 12, inclosing the sides, ends and bottom of the receptacle. The frame 11 is supported with curved flanges or hangers 13, adapted to engage the upper edge 14 of the wash-boiler 15 to support the receptacle A. Said receptacle is preferably made to conform to the shape of the boiler at one end 30 and to occupy about half of its length and depth, the purpose being to suspend it above the water in the boiler by the hangers 13 and leave a space at one end of the boiler for lifting the boiled articles from the water.

35 Said receptacle is also provided with the handles 16 for conveniently adjusting the hangers 13 on the boiler and also to remove the receptacle A when it is filled with boiled laundry pieces.

40 The squeezer B is also composed of wire mesh fabric mounted upon the frame 17 and conforms to the outlines of the upper portion of the receptacle A, being adapted to fit snugly therein. It is of course understood 45 that the squeezer B should be of sufficiently heavy wire, properly reinforced by the frame 17, to make the squeezer rigid, so that it may be used to apply considerable pres-

sure to the wet articles in the receptacle A. A handle 18 is also provided on the top of 55 the free end of the member B by means of which the squeezer may be lifted or pressed into the receptacle A when the latter is filled with the articles removed from the boiler.

50 In operation the articles to be laundried are boiled in the usual way, after which they may be removed from the boiling water by means of the wash stick 19 (see Fig. I) and placed in the receptacle A. When sufficient articles from the boiler have been placed in 55 said receptacle the squeezer B is turned by means of the handle 18 to the position shown in Fig. II, when enough pressure may be applied to the laundried articles to remove 60 much of the excess water therein, it being 65 noted that it is desirable to have the surface of the boiling water somewhat below the base of the receptacle A so that natural 70 drainage will assist in removing the water from the boiled articles. After the removal 75 of the free water in the manner indicated my device may be lifted from the boiler by means of the handle 16 and the articles 80 therein may be removed to be placed in rinsing water or otherwise disposed of.

Having described my invention what I claim as new and desire to protect by Letters Patent is:

1. A foraminous basket-shaped receptacle 85 having substantially vertical sides and provided with hangers for engagement with the upper edges of a boiler, a foraminous squeezer hinged at one end to said receptacle and adapted to fit snugly into the upper portion thereof and a handle upon the free 90 end of said squeezer for pressing the same upon the contents of said receptacle.

2. A foraminous receptacle formed and arranged to fit into and partially occupy the opening in the top of a boiler and provided 95 with hangers for engagement with the upper edges of a boiler, a foraminous basket-shaped squeezer adapted to fit snugly into the upper portion thereof and a handle upon the upper side of the squeezer for pressing 100 the same upon the contents of said receptacle.

Whereof, I have hereunto signed my name to this specification.

MRS. LENA J. SYVERSON.
